UNITED STATES PATENT OFFICE.

GUSTAV WITTE AND OTTO GREINER, OF BERLIN, GERMANY.

EXTENSION FIRE-LADDER.

SPECIFICATION forming part of Letters Patent No. 291,259, dated January 1, 1884.

Application filed July 14, 1882. (No model.) Patented in Germany August 16, 1879, No. 9,806, and June 9, 1882, No. 21,092, and in Austria-Hungary October 31, 1882.

To all whom it may concern:

Be it known that we, GUSTAV WITTE and OTTO GREINER, subjects of the King of Prussia, residing at Berlin, Germany, have invented 5 certain new and useful Improvements in Fire-Ladders with Manipulating Devices; and we do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Our invention relates to certain improvements in the construction of extension fire-ladders, and in mechanism for extending or erecting and lowering the same, as hereinafter fully described, and as shown in the accompanying 20 drawings, in which—

Figure 1 is a sectional elevation of an extensible fire-ladder constructed to be supported from and carried upon a four-wheeled truck. Fig. 2 is an end view, and Fig. 3 a top plan view, thereof. Figs. 4, 5, 5^a, 5^b, 5^c, 5^d, and 5^e are detail views, the latter on an enlarged scale. Figs. 6, 7, and 8 are detail views of a modified construction of mechanism for raising the ladder-sections, said mechanism 25 being constructed to be mounted upon and carried by a four-wheeled truck. Fig. 9 is a longitudinal section of an extension fire-ladder and its elevating mechanism supported from and carried upon a two-wheeled truck, the 30 sections of the ladder being shown in position for transportation. Fig. 10 is a sectional end view thereof. Fig. 11 shows in side elevation the parts in position for extending and raising the ladder. Fig. 12 is a front elevation there- 35 of, partly in section. Figs. 12^a and 12^b are detail views on an enlarged scale, showing the construction of the slide or carriage C². Figs. 13 and 14 are detail views, showing our improved construction of ladder-sections. Fig. 40 15 is a detail view of part of the mechanism used for extending the ladder. Fig. 16 shows in section our improved coupling for coupling the ladder-sections together. Fig. 17 is a plan view, and Fig. 18 a detail view, thereof.

Like letters of reference are employed to indicate like parts wherever such may occur in the above figures of drawings.

Our invention consists in mechanism and combination of mechanisms for extending and raising the ladder section by section, commencing with the upper section and building such ladder from top downward, for adjusting the ladder when extended and raised into proper position, and securing such ladder into the position in which it has been adjusted, 50 substantially as hereinafter fully described.

Various mechanical devices may be employed to carry out our invention, which may be applied to a four-wheeled vehicle or truck or to a two-wheeled vehicle or truck, both of 55 which we have illustrated in the accompanying drawings; and that our invention may be fully understood we will first describe the same as applied to a four-wheeled truck, referring more particularly to Figs. 1 to 8, in- 60 clusive.

The apparatus consists of a number of ladder-sections of any usual or desired construction, preferably of the construction hereinafter described, and which may also be used as 75 hand-ladders, these ladder-sections L being so constructed that the upper end of the side bars of one section may be fitted into sockets formed at or attached to the lower end of the side bars of another section, as shown in dotted lines in 80 Figs. 1 and 4, and as hereinafter further explained, said sections being braced together by side-rail braces, or rigidly connected by couplings or bolts.

Upon the rear end of a suitably-constructed 85 four-wheeled carriage or truck, T, is located a disk or turn table, T', mounted upon a spindle or vertical pivot, p, and adapted to be rotated by hand through the medium of a worm-gear, w, or other suitable gearing. The turn-table is provided with bearings, in which are mounted the ends t of a shaft or cross-girt, G, that connects the standards f at their lower end, said standards being connected by a cross-girt, G', at their upper end, as shown in Figs. 90 2, 3, 5^a, 5^b, and 5^c. Said turn-table also carries mechanism for holding the frame in proper position when raised and preventing its displace- 95

ment, which mechanism may consist of a worm-segment and worm, or, as shown in Fig. 1, of a toothed segment, s , and pinion P' , or of any other appropriate mechanical appliances whereby the frame may be securely held in any desired position. The frame F is composed of two longitudinal girts, f , of metal, of rectangular or $\mathbf{U}$ shape in cross-section, their plane surfaces facing each other. To these plane faces are bolted similar girts, f' , of less diameter, the channel of which serves as a guide or way in which reciprocate two carriages, C C' , that serve to move the ladder-sections toward the outer end of the frame, said sections, when laid on the carriages, being guided by the standards or girts f , which are of greater diameter than the ways f' , as above stated. The carriages are connected to the ends of chains c and c' . The chain c passes over pulley p' , fast on its shaft, its ends being connected to the carriages C and C' by means hereinafter described, and the chain c' , whose ends are also connected to said carriages, passes over a loose pulley, p^2 , said chains forming a double loop and serving to impart a reciprocating motion to the carriages C C' , as follows: S' is a shaft mounted in frame F , that carries suitable crank-handles, h , and a transmitting-pulley, p^3 , connected by belt or chain c^2 with a second transmitting-pulley, p^4 , upon a shaft, S^2 , also mounted in frame F , which latter shaft carries a pinion, P , that meshes with a toothed wheel, W , mounted upon the shaft of the chain-pulley p' , as plainly shown in Fig. 2. By rotating the shaft S' in one direction the two carriages C C' will approach each other, and by rotating said shaft in a reverse direction they will recede from each other. The ladder-sections are held by means of pawls 40 arranged on opposite sides of the carriages C C' .

As plainly shown in Figs. 5^a, 5^b, 5^c, and 15, each carriage C C' has an axle, a^2 , carrying at their opposite ends pawls a a' , and a' a' respectively, the arm a^2 of which is adapted to enter into a recess, g , formed in a plate, g , secured to the under side of the end spokes of each ladder-section, said arm a^2 being held in proper position for engaging with the recessed plate by its weighted arm a^1 . The axle a^2 carries a cam or lug, a^5 , with which engages a stud or pin, k , projecting from a lever, K , by means of which the arm a^2 of the pawl may be depressed out of the path of the plates g when the ladder-sections are lowered in dismembering the ladder. If the carriages C C' (shown in Fig. 2) are brought to the limit of their movement from each other, and a ladder-section, L , is placed on the frame F upon said carriages, so that the pawls of carriage C will engage the recessed plate g of the last spoke at the lower end of said section, and the crank-shaft S' is rotated to bring the carriages together, the ladder-section will be raised a distance equal to its length, and the pawls a' of the carriage C' will be in position to engage with the recessed plates g on the under side of

another spoke of the ladder-section—say the second or third spoke from the lower end of said section, as shown in Fig. 5^c. If, now, the motion of the crank-shaft is reversed, the pawls a of carriage C will move out of engagement with their recessed plates, and simultaneously therewith the pawls a' of carriage C' will move into engagement with their recessed plates, the carriage C moving down and the carriage C' up, carrying with it the ladder-section, (or sections, as the case may be,) which is now held by pawls a' , and has again been moved up a distance equal to its length. This latter movement clears the frame for the insertion of a second ladder-section—that is to say, a second section may now be laid upon the guide-frame F and the carriages and the upper end of its side bars inserted into the lower socketed end of the first section. When this has been done, the brace-rails R are applied to brace the ladder-sections together and form at the same time hand-rails, as shown in Figs. 1, 4, and 5. The operation hereinabove described to raise the second section is repeated, and so on for each section, until the ladder is of the desired or required length. The lowering of the ladder and its dismemberment takes place in reversing the operations above described, the pawls a' of carriage C' being held out of the way of the recessed plates g of the ladder-sections, by means of any suitable mechanism adapted to be operated by hand, until said pawls have passed the recessed plates. For this purpose the pawls a' may be mounted upon a shaft adapted to be rotated by a crank; or said pawls may be held out of the way of the recessed plates by any other suitable means—as, for instance, a lever actuating an arm on the pawl-pivot or the pawl, as shown in Fig. 15. To give the frame F and the ladder the necessary inclination, the crank-handles h are connected with shaft S' , carrying the pinions p^5 , that mesh with the gear-wheels W' , the shaft S^2 of which carries the pinions P' , that mesh with the toothed segments s . We provide also the usual safety appliances to catch the ladder in case of its fall with a wall, at any elevation, either by means of detents or other suitable and well-known mechanism, which need not here be described in detail, as they form no part of this invention.

In Figs. 6, 7, and 8 we have shown a modified construction of mechanism for raising the ladder-sections and forming the ladder. The guide-frame F (shown in the latter figures) consists of two $\mathbf{U}$ -shaped iron side pieces, f , connected at one end by a transverse bar or girt, G , the ends of which are formed into trunnions t , that rotate in bearings B B' , secured to the turn-table T' . To one of the side pieces f is bolted a bearing, B' , in which is mounted a shaft, S^3 , that carries a pinion or toothed wheel, W^2 , that meshes with a rack-bar, R' , arranged to slide in said side pieces, f , of frame F . The shaft S^3 also carries a worm-wheel, W^2 , that meshes with a worm-spindle,

w' , by means of which the rack-bar is moved when said worm is rotated. The upper end of the rack-bar has an arm, r , to which is connected a transverse bar or girt, G' , the ends 5 of which are formed into trunnions t' , upon which the upper ends of two brace-rods, E E' , are pivoted, the lower ends thereof being pivoted either upon pins or short shafts S' , mounted in bearings B' , secured to or 10 formed upon the turn-table T' , or upon a common shaft mounted in such bearings.

Upon the lower end of the frame F are mounted the chain-pulleys $p' p^2$, whereby the extension and raising of the ladder is effected, as hereinbefore described. When the worm-gearing is operated to move the rack-bar upward, then the braces E E' will swing in the arc of a circle, (shown in dotted lines, Fig. 6,) whereby the entire frame is displaced, 15 said frame inclining toward the right. The frame F lies horizontally upon the truck that serves for its transportation and for the transportation of the ladder-sections, of which truck the turn-table forms a part, and when 20 it is desired to raise the frame the trunnions t are laid into the bearings B , and secured therein by means of the caps b b of said bearings, as shown in Fig. 6.

We have deemed it unnecessary to show the 30 truck in relation to Figs. 6, 7, and 8, as said truck is or may be of a construction substantially like that shown in Figs. 1, 2, and 3.

The mechanism described serves not only to determine the position in which the frame is to be held when raised, but also to lower it into a horizontal position by simply removing the trunnions t t from their bearings and allowing the frame to swing upon the brace-rods into a horizontal position upon the truck. 35 The principal object in view is, on the one hand, to effect the displacement of the upper end or apex of the frame F , to give the ladder the necessary inclination, by the application of as little power as possible, and in such manner as to insure the stability of the frame, to whatever position it may be shifted, and, on the other, to shift the frame into the required position for action in as little time as possible.

In Figs. 9 to 18 we have shown a construction of extension fire-ladder adapted to be mounted on and carried by a two-wheeled truck. The main frame in this modification is in its general features substantially like the frame described in reference to Figs. 6, 7, 50 and 8.

Instead of a rack-bar and worm-gear for adjusting the frame in the desired position, we employ a slide or carriage, C' , that embraces one of the side flanges of the U-irons of the frame, and to the opposite side of said carriage or slide are pivoted the braces E E' , as more 55 plainly shown in Fig. 12*. The carriage or slide consists of a transverse plate or body, e , the ends of which are bent to embrace the inner side flange, f^1 , of the U-shaped side bars of the frame F , as plainly shown in Fig. 12*. Upon the bent portion e' of the carriage is

formed a bearing in which is mounted a pawl, M , held with its arm extended against the outer flange, f^3 , of the side bars of frame F , by a spiral 70 spring, m . This pawl, when the frame is elevated into proper position, abuts against a stop-plate, m' , to hold said frame in the position into which it has been adjusted. Any desired number of such plates may be affixed to the 75 said side bars to give the frame any desired inclination. To allow the pawl to pass by the stop-plates, it is provided with a handle, m^2 , by means of which it may be turned out of the way of the plates, as plainly shown in 80 Figs. 11, 12*, and 12**.

To the carriage C' are attached chains H , that travel over chain-pulleys H' H^2 , mounted on suitable shafts rotating in bearings secured to the side bars, f , the arrangement of the 85 chains being substantially like that for moving the carriages C C' —that is to say, by rotating one or the other drum the carriage is moved up or down along the side bars. These means for imparting a reciprocating movement to 90 such carriage are well known, and need therefore no further description.

The frame F , instead of being mounted upon a turn-table, is constructed and arranged for operation as follows: The trunnions t t of the 95 lower transverse girt, G , form the axles of two small carrying and guide wheels, W^2 , which serve to facilitate the erection and placing into position of said frame F . The two brace-rods E are pivoted at one end to the transverse girt 100 G' or axis that connects the carriage C' , and their other end is pivoted upon the axle A of the truck-wheels W^1 . The other two braces, E' , here take the place of the turn-table to form a rigid base to the frame, and they are pivoted 105 upon the transverse girt G of the frame at one end, and at the other upon said axle A of the truck-wheels W^1 , as plainly shown in said Fig. 11. It is evident that when the carriage C' is moved upward the frame will incline in 110 one direction, and when moved downward said frame will incline in an opposite direction, the braces E rotating upon the axle A of the truck-wheels. The mechanism for extending and 115 raising the ladder is substantially like that hereinbefore described.

C and C' are the sliding carriages traveling upon the U-shaped frame-pieces f f , and they are moved, as described, by means of chain-pulleys and chains and suitable gearing. 120 These carriages are also provided with the pawls a a' , that engage recessed plates g on the under side of the spokes of the ladder-sections. In Fig. 15, which shows a transverse section of the carriage C' on a larger scale, the 125 means employed for connecting the operating-chains c c' are plainly shown.

D D' are tubular bearings to receive the bolts d d' , that carry nuts n n' n'' n''' , respectively, upon opposite sides of the bearings D 130 D' . The outer ends of the bolts are provided with suitable bearings for the reception of a pivot-pin, d^2 , to which the outer end of the chains c c' is connected. By means of this

construction the slack, if any occurs, in the chains may be readily taken up by loosening the nuts n^2 and n^3 , and then tightening up the nuts n^1 and n^4 , as will be readily seen from an inspection of the drawings.

We have hereinbefore described sectional ladders of any suitable construction provided at their lower end with sockets and recessed plates g , the former to receive the upper end 10 of a ladder-section, and the latter to provide a hold whereby said ladder-sections are carried upward for extension. Such a construction of ladder, no doubt, will answer all the purposes for which they are designed; but as 15 our object is to make this class of apparatus as efficient and strong as possible, we prefer to employ the construction of ladder-sections shown in connection with the form of apparatus just described, and as shown in Figs. 9 to 20 14 more particularly. The sections L of the ladder have tubular side pieces or bars, l —that is to say, the side pieces are made from ordinary iron or steel piping of suitable diameter, to which wooden or other steps or rungs 25 I , may be connected in any suitable manner, as by means of bolts passing through the side bars, l . This would, no doubt, greatly facilitate the construction of the ladder-sections, but it would materially weaken the side bars. To 30 avoid this we prefer to attach the steps I by means of two-part clamps i , having flanges i' , whereby said clamps may be bolted to the side bars, l .

Instead of inserting the side bars of one section 35 into the sockets of the side bars of another section, as described, we prefer in this construction of ladder to couple the sections together by means of an improved coupling which is constructed for application and operation as follows, referring more particularly 40 to Figs. 16, 17, and 18, which illustrate the coupling on an enlarged scale. The lower extremity of the side bars, l , of the ladder-sections L is of a less diameter than the upper 45 extremity of said side bars, and upon the former is secured a screw-threaded ring, M , upon which screws an interiorly-threaded sleeve, O , the lower interior periphery of which is hook-shaped, as shown at o , the hook-shaped periphery o being cut away on opposite sides, to 50 form recesses o' , as shown in Fig. 18. The upper end of the side bars of the ladder-sections is provided with a head or annular shoulder, l' , that is, like the sleeve O , hook-shaped at its lower end. The outer diameter 55 of the shoulder l' is made to correspond with the hooked portion of sleeve O —that is to say, it is cut away, so as to enable it to be slipped past said hooked portion, the part cut away 60 corresponding with the hooked portion o of sleeve O , and the hooked portion of the shoulder l' corresponds to that portion of the sleeve O which is cut away, thus forming an interlocking joint. It is evident that when the 65 two parts have been slipped past one another and the sleeve O is rotated the said parts will not only become locked, but they will also be

drawn together, as will be readily understood. The sleeve O at its upper end is of smaller diameter than at its lower, forming a shoulder, o^2 , upon which is seated a ring or sleeve, q , to which is secured, or upon which is formed, a tubular arm, q' . At its inner end the arm is screw-threaded interiorly, into which is screwed an eyebolt, q^3 . The inner end of the eyebolt lies in a recess, o^3 , formed in the periphery of the sleeve O , whereby said sleeve is rotated, the arm and bolt constituting the operating-lever. This construction of operating-lever is of great importance, inasmuch as it provides 70 means whereby the lever may be brought into such relation with the ladder as to be entirely out of the way of the firemen. It is obvious that by unscrewing the eyebolt to retract it from the recess o^3 after the coupling has been 75 effected, the sleeve q may be rotated to bring the lever on a line parallel with the steps of the ladder, and if the bolt is now again screwed home it will be held in that position and may serve as an intermediate step between the ladder-sections. 80

Having thus described our invention, what we claim, and desire to secure by Letters Patent of the United States, is—

1. In an extension fire-ladder, the combination, with a series of ladder-sections constructed to be connected one with the other by socket-joints on their side bars, of a frame, F , two reciprocating carriages, $C C'$, and means, substantially as described, for imparting motion to said carriages and holding the ladder-sections in position when raised, whereby a ladder-section is raised and held for connection with another section to build the ladder from top downward and raise the ladder as it is built up, substantially as described. 95

2. In an extension fire-ladder, the combination, with ladder-sections adapted to be connected by socket-joints, of a frame and two reciprocating carriages supported thereon, and constructed to serve as a guide for said carriages and for the ladder-sections when placed thereon, mechanism for moving the carriages in opposite directions to raise a ladder-section, devices to hold said section in position for connection from below with another section, and mechanism for adjusting the ladder when built up into proper position and giving it the proper inclination, substantially as described. 110

3. In an extension fire-ladder, the combination, with ladder-sections constructed to be connected by socket-joints, of a frame and mechanism for raising the ladder-sections one after another, appliances for rotating the frame and giving it the proper inclination, and mechanism for rigidly holding the ladder and frame in the position given thereto, substantially as set forth. 120

4. In an extension fire-ladder, the combination, with a two-wheel truck, of the hinged or folding frame F , supported at one end of its base by guide-wheels and at the opposite end from the truck-wheel axle, and mechanism for elevating the frame and adjusting the same to 130

the desired inclination, as described, for the purpose specified.

5. The frame F, composed of side pieces, f, brace-rods E E', and cross-girts G G', all constructed for operation in combination with a truck or carriage, substantially as shown and described, for the purpose specified.

6. In an extension fire-ladder, the frame F, composed of side pieces, f f, brace-rods E E', cross-girts G G', and the guide-wheels W³, in combination with the axle of a truck, upon which said ladder is adapted to be folded, as described, for the purpose specified.

7. In an extension fire-ladder, the frame F, composed of side pieces, f f, brace-rods E E', cross-girts G G', and guide-wheels W³, in combination with the carriage C², mechanism for moving the same along the side pieces, f, and the axle of a truck, upon which said frame is adapted to be folded, as described, for the purpose specified.

8. The combination, with two sections of tubing and the coupling O, constructed as shown and described, of a ring or sleeve carrying an operating-lever and constructed to be 25 fitted upon the sleeve O, for rotating the same, substantially as and for the purpose specified.

9. The combination, with the sleeve O, having shoulder o² and a recess, o³, of the ring q, its tubular arm q', and the eyebolt q², all constructed for operation substantially as described. 30

In testimony whereof we affix our signatures in presence of two witnesses.
